UNITED STATES PATENT OFFICE

101,383

DESIGN FOR A MANTEL ORNAMENT

Edward W. Menger, San Antonio, Tex.

Application August 1, 1936, Serial No. 64,194

Term of patent 14 years

To all whom it may concern:

Be it known that I, Edward W. Menger, a citizen of the United States and a resident of San Antonio, in the county of Bexar and State of Texas, have invented the new, original, and ornamental Design for Mantel Ornaments, of which the following is a specification:

Reference is had to the accompanying drawing, forming part thereof.

I claim:

The ornamental design for a mantel ornament, as shown.

EDWARD W. MENGER.
